UNITED STATES PATENT OFFICE.

JOSEPH BELL, OF CINCINNATI, OHIO, ASSIGNOR OF ONE-HALF TO GUSTAV W. EISENHOHR, OF CINCINNATI, OHIO.

ELECTRIC GENERATOR.

1,163,501.

Specification of Letters Patent.

Patented Dec. 7, 1915.

Application filed August 17, 1914. Serial No. 857,184.

To all whom it may concern:

Be it known that I, JOSEPH BELL, a citizen of the United States, residing at Cincinnati, in the county of Hamilton and State of Ohio, have invented new and useful Improvements in Electric Generators, of which the following is a specification.

My invention relates to improvements in that type of electric generators where the armature rotates in one direction and the field in the other; and consists in a new and useful combination of parts, forming a very simple machine of great efficiency. The casings or supporting body for these elements are made of equal diameter and of equal or approximately equal weight when complete so as to operate as flywheels to regulate the motion and are driven by direct pitman connection with a reciprocating steam or other motor without gearing, belting, hollow shafting or other extraneous connections. The generator thus constructed is of practically double efficiency for a given motor-speed; and, obviously, for given relative speeds of armature in relation to the field is more economical both in the expenditure of power, cost of construction and of maintenance, besides possessing the advantages of reduced space and weight. Should either of the motor connections become disabled, the pitmen may be removed and that rotating element secured against rotation and the dynamo kept in operation for the time being thus securing operation at the efficiency of an ordinary generator instead of shutting down the dynamo altogether.

My invention is illustrated in the accompanying drawings in which—

Figure 1 is a top plan view of a dynamo whose elements rotate in opposite directions and a single-cylinder reciprocating engine and pitman connections for operating said dynamo; Fig. 2 is an end elevation of the frame, showing the armature and field cases in section, the driving mechanism being omitted.

Referring now to the drawings, A is a crank-shaft journaled on the pillow blocks e^9 , e^{10} with an armature casing a^1 fixed to the inner end of said shaft. This casing a^1 is made heavy on the rim a^3 to act as a flywheel, and is shown in the drawing with its spokes bent inwardly so as to economize space and bring the crank a closer to the

casing. The casing a^1 carries the armature laminations a^2 and electrical connections.

The crank shaft F which has a crank f is journaled in the axial line extended of shaft A on the pillow blocks e^7 e^8 , with a field casing f^1 fixed to the inner end of said shaft, and a rim f^3 all similar in all respects to the casing and its accessories upon the shaft A. The cores f^2 are built up in the casing f^1 . A pitman e^6 connects the crank f , and a pitman e^5 connects the crank a with opposite ends of a wrist-pin e^4 through the cross-head e^1 operating in the usual guides. This cross-head is attached to the piston-rod e of the single cylinder engine E.

The arrows on the casings a^1 and f^1 indicate that they are intended to be rotated simultaneously in opposite directions and with the connections shown in Fig. 1 this may be effected by the same reciprocating source of power. With such connections in starting the engine one crank should be up and the other down, so that the initial impulse will drive the shafts A and F in opposite directions, which relation is maintained through the action of the rotating field and armature casings operating as regulating flywheels, each in relation to its shaft.

I claim as my invention and desire to secure by Letters Patent of the United States.

1. An electrical machine embodying two non-contacting crank shafts mounted to rotate in a common axial line extended; an armature carried by one of said shafts, and a corresponding field element by the other in operative relations each with the other; pitmen connected at one end with the cranks of said crank shafts respectively, and at the other with a common reciprocating driving motor to rotate said field and armature simultaneously in opposite directions.

2. An electric generator embodying a field and an armature adapted to operate as flywheels, two crank shafts journaled in the same axial line extended and carrying said field and armature in operative relations, and a cross-head provided with means for its reciprocation and pitmen connecting said cross-head and crank shafts.

3. An electric generator embodying a supporting frame; pillow-blocks for independent crank shafts to operate in a common axial line; a stationary cylinder arranged at right angles with these; guides in or parallel with the extended axis of said cylinder,

two independent crank shafts, carrying circular field and armature elements respectively, a cross-head and piston operated by said cylinder and pitmen connecting the 3 cross-head and crank shafts.

4. In an electric generator the combination of a supporting frame, pillow blocks for two independent crank-shafts adapted to operate in a common axial line, said crank-shafts, rotatively attached to one crank-shaft a field casing weighted to form a fly-wheel, a field built up in said casing rotatively attached to the other crank shaft

an armature casing weighted to form a fly-wheel, an armature built up in said casing, a reciprocating engine, a cylinder at right angles to said crank shafts, a piston and cross-head operated by said cylinder, and pitmen connecting the cross head and crankshafts. 15

In testimony whereof I have hereunto set 20 my hand in presence of two subscribing witnesses.

JOSEPH BELL.

Witnesses:

WALTER A. KNIGHT,
LEWIS M. HOSEA.

Correction in Letters Patent No. 1,163,501.

It is hereby certified that the citizenship of the patentee in Letters Patent No. 1,163,501, granted December 7, 1915, upon the application of Joseph Bell, of Cincinnati, Ohio, for an improvement in "Electric Generators," was erroneously given as "the United States," whereas it should have been given as *Empire of Austria-Hungary*; and that the said Letters Patent should be read with this correction therein.

Signed and sealed this 1st day of February, A. D., 1916.

[SEAL.]
